SHOWER HEAD

William Bruce Delamater, 9114 Valley View,
Whittier, Calif. 90603

Filed Dec. 5, 1966, Ser. No. 4,924

Term of patent 14 years

(Cl. D91—3)

FIG. 1.

FIG. 2.

FIG. 3.

FIG. 4.

I claim:

The ornamental design for a shower head, substantially as shown.
